F. J. DOWLING.
FLUSH TANK VALVE.
APPLICATION FILED JUNE 6, 1918.

1,300,138.

Patented Apr. 8, 1919.

FIG. 1.

FIG. 4.

UNITED STATES PATENT OFFICE.

FRANCIS J. DOWLING, OF NEW YORK, N. Y.

FLUSH-TANK VALVE.

1,300,138.

Specification of Letters Patent.

Patented Apr. 8, 1919.

Application filed June 6, 1918. Serial No. 238,572.

To all whom it may concern:

Be it known that I, FRANCIS J. DOWLING, a citizen of the United States, and a resident of the city of New York, borough of Manhattan, in the county and State of New York, have invented a new and Improved Flush-Tank Valve, of which the following is a full, clear, and exact description.

This invention relates to details of plumbers' fittings, and has particular reference to valves for flush tanks with a view to making such valves non-leakable. While I show my improvement as applied to the bottom of a flush tank fitted with a delivery siphon, I wish it to be understood that certain features of my improvement are adapted to be used in connection with tubs, wash basins, sinks, or other receptacles, and hence I do not desire to be limited in the interpretation of the claims except as may be required by the state of the art.

Among the specific objects that I have in view is to provide an improved valve structure comprising what may be called a wedge seat and a movable valve member coöperating therewith and having a complementary seat groove or channel adapted to contact on both sides or surfaces of the wedge seat.

Another object of the invention is to provide improved facilities for insuring the prompt and automatic seating or closing of the valve.

A still further object is to provide an improved delivery pipe coupling means either with the spud or the lock nut that secures the spud, providing for the direct delivery of all the water free from the upper edge or end of the delivery pipe or well down into the pipe so as to prevent any possible leakage to the outside of said pipe.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical central sectional view on line 1—1 of Fig. 2, and represent-

ing certain features of my improvement associated with flush tank siphons. 55

Fig. 2 is a horizontal section on the line 2—2 of Fig. 1.

Fig. 3 is a vertical sectional detail showing a modification in which the spud and delivery pipe funnel connection are indicated. 60

Fig. 4 is a detail view of another modification in which the spud is made in two parts, the valve seat being integral with one part and the funnel being integral with the other part; and 65

Fig. 5 is a further modification in which the valve seat is integral with the spud and the combined locking nut and funnel structure of a form similar to that of Fig. 1 which coöperates directly with the spud. 70

Referring now more particularly to the drawings, I show in the first figure a portion of the bottom 10 of the flush tank or analogous receptacle. 11 is a spud projecting through the bottom 10 and having at its upper end or edge integral features as follows: An inwardly projecting flange 12, an outwardly projecting flange 13, shown in Fig. 1 as lying in the same plane substantially as the flange 12, and an upstanding flange or rim 14 of about the same diameter as the main portion of the spud. This rim 14 is preferably screw threaded on one surface, as for example the outer surface. Furthermore the body of the spud is provided at or adjacent to its lower end with a screw thread, this being indicated as preferably on the outer surface for the accommodation of the lock nut 15 whereby the spud is clamped to the bottom 10, a gasket 16 of rubber, or its equivalent, being interposed between the upper surface of the bottom and the outwardly projecting flange 13. In Figs. 1 and 5 the lock nut 15 includes an integral tail piece or funnel structure 17 having an externally threaded portion 18 constituting a shoulder against which the upper flanged end of the delivery pipe 19 is adapted to be fitted and locked by means of a coupling nut 20. The tail piece or funnel 17 projects well downward into the end of the pipe and so overlaps the joint between the pipe and the coupling nut. Hence with the upper end of the spud sealed by means of the washer 16 against leakage no water can pass between 95

the outer wall of the spud and the bottom 10. 100

to the joint between the lock nut 15 and the lower end of the spud, nor between the lock nut and the bottom surface of the member 10. Hence all water that passes through the 5 spud must be delivered through the funnel into the pipe 19 well below the joints.

The siphon structure illustrated includes an inner tube 21 of any suitable construction or length, the lower end of which is slotted 10 at 22 leaving three hangers 23 each of which has an outwardly projecting foot or segmental flange 24 forming a base for a coil spring 25 surrounding the tube. The upper end of the spring bears against the inwardly 15 projecting flange 12 above referred to in the form shown in Fig. 1, and the tendency of the spring is to cause the tube 21 to be projected downward automatically when the siphon structure is released at the flushing 20 operation. It will be noted that the slots 22 are open and unobstructed at their lower ends so that there is no interruption of the free flow of water through the valve in initiating the siphonic action, and no mud, 25 sediment, or the like can accumulate therefore at the lower end of the tube.

The valve comprises a seat 26 which may be made of any suitable material either metal or otherwise, the same being provided with a 30 circumferential slot 27 whereby it may be secured as by screw threads upon the rim 14. This seat may be described as of a wedge shape having inner and outer surfaces at 28 and 29 respectively formed at an angle to 35 each other. The upper edge portion of the seat where the contact surfaces meet may be obtuse, rounded, or any other suitable shape flatter than a sharp angle so as to insure the best operation of the valve. I provide also as indicated at 30 an outer downwardly projecting flange adapted to bear 40 against the upper surface of the washer 16 whereby water is prevented from passing between the valve seat and the washer. The 45 other member of the valve is indicated at 31 and will be referred to hereinafter as the valve as distinguished from the valve seat. This member 31 is secured in any suitable manner as by screw threads to the tube 21 50 whereby it is fixed to and movable therewith into and out of contact with the valve seat. The valve is provided with inner and outer contact surfaces 32 and 33 respectively arranged at an angle to each other corresponding 55 to the angle between the surfaces 28 and 29 of the valve seat with which they engage respectively simultaneously. The two surfaces 32 and 33 are so formed in the lower portion of the valve as to form a more 60 acute angle than the meeting line or surface between the contact surfaces 28 and 29 thereby observing a space 34 between the two valve members when the valve is seated and providing for a considerable amount of 65 wearing between the valve members before

the third seat of the valve becomes effective at the apex.

In Fig. 3 the general construction is the same as that in Fig. 1, but different, however, in that the spud 11^a is made integral 70 with the funnel structure 17^a and the flange 12 is omitted, the spring 25 bearing at its upper end directly against the valve seat 26 which is indicated as of the same structure as in Fig. 1, the lock nut 15^a acting for the 75 same purpose as above indicated to lock the spud with its flange 13 against the gasket 16, but this lock nut is independent of the funnel. The valve 31 is shown as having the same characteristics as set forth above in 80 connection with Fig. 1.

Fig. 4 covers a structure in which the spud is made in two parts, the upper part 11^b being integral with the valve seat 26^b while the other part thereof with which the lock nut 15^b coöperates is integral with the funnel 17^b. In this form the valve seat 26 takes the place of the flange 13 as well as the flange 12 of Fig. 1, but possesses the same features with respect to the wedge shaped or angularly disposed contact surfaces 28 and 29. Fig. 5 shows a still further variation embodying certain features of Fig. 1 and others of Fig. 4. The spud 11^c is made integral 90 with the valve set 26^c which bears against 95 the washer and the spring as in Fig. 4, while the lock nut operates the same as in Fig. 1 and has combined with it the funnel 17.

In the operation of my improvement the 100 siphon is lifted by any suitable actuating means, not shown, but connected to the hook 35 connected to the top of the dome 36 and by means of a hanger 37 to the upper end of the tube 21 constituting the down leg of the 105 siphon whereby the valve 31 is unseated allowing the water in the tank to flow freely inward and downward through the slots 22 in sufficient volume to initiate the siphonic action when the valve is automatically reseated by the action of the spring 25, or its equivalent. The coöperating contact surfaces of the valve members arranged at an angle to each other insure that there must be a true seating action even though both members may be made of metal, and in the event of wear upon the valve members there will still be insured a water tight joint until the apex of the groove between the two surfaces 32 and 33 is reached, when one or the other 110 of the valve members may be required to be renewed.

The flange 13 of the spud that bears against the outer surface of the washer 16 is provided with circular corrugations or 125 teeth 13', each tooth being provided preferably with an outer vertical wall and an inner inclined wall. These teeth or corrugations projecting into the compressible washer make the seal much more effective 130

than if no teeth were provided, and furthermore the vertical outer walls of the teeth make it even more difficult for water to creep through between the washer and the part coöperating therewith. The valve seats shown as parts of the spuds are also preferably provided with similar teeth 13'.

I claim:

1. In a valve structure of the class set forth, the combination of a valve seat having two conical contact surfaces diverging from each other at equal angles from the vertical, the meeting edge thereof being obtuse, means to hold the seat in position, a valve having a groove bounded by two contact surfaces similarly inclined to the respective contact surfaces of the seat with which they coöperate simultaneously, the valve contact surfaces meeting each other in an angle relatively sharper than the apex of the seat aforesaid, and means to support and manipulate the valve with respect to the seat.

2. In a valve construction for a flush tank having a bottom, the combination of a spud extending through the tank bottom, a washer surrounding the spud, a valve seat associated with the spud and bearing against the washer, a valve coöperating with the valve seat, a tubular member to which the valve is connected, said tubular member projecting downward through the valve seat into the spud and below the tank bottom, and means acting upon the tubular member to automatically seat the valve, said valve seat and valve having a plurality of coöperating contact surfaces.

3. In a flush tank valve, the combination of a spud, a valve seat carried by the upper end of the spud, a washer sealing the joint between the valve seat and the tank bottom, said valve seat having a downwardly projecting flange surrounding the spud and bearing directly against said washer, a delivery pipe, means to connect the delivery pipe with the spud, a funnel construction associated with the spud and extending

within the pipe, a valve coöperating with the seat, and means to control the action of the valve with respect to the seat.

4. In a flush tank valve structure, the combination of a spud, a valve seat carried by the upper end of the spud, a tubular member projecting downward through the valve seat and spud and having open ended slots at its lower end and having outwardly projecting feet between the lower ends of the slots, a coil spring surrounding the tubular member and bearing at one end against said feet and at the other end against the spud and valve seat structure, and a valve carried by the tubular member and caused by the action of the spring to seat automatically on the valve seat.

5. The herein described valve construction comprising a spud, a valve seat removably attached to the upper end of the spud, an integral funnel construction extending downward from the spud, a discharge pipe fitting over the funnel construction, means to lock the pipe to the funnel, a valve coöperating with the valve seat, a tubular member to which the valve is connected and extending into the spud, and means acting upon the lower end of the tubular member and against the bottom of the valve seat tending to hold the valve seated.

6. In a flush tank valve structure, the combination of a spud, a valve seat carried by the upper end of the spud, a tubular member projecting downward through the valve seat and spud and having passageways therethrough and being provided at its lower end with a spring base, a coil spring surrounding the tubular member and bearing at one end against said spring base and at its other end against the valve seat structure, and a valve carried by the tubular member above said passageways and caused by the action of the spring to seat automatically on the valve seat.

FRANCIS J. DOWLING.
